UNITED STATES PATENT OFFICE.

MATTIE R. WARD, OF LEESVILLE, LOUISIANA.

DESIGN FOR A CURTAIN-POLE.

40,571.

Specification for Design.

Patented Mar. 8, 1910.

Application filed January 15, 1910. Serial No. 538,296. Term of patent 7 years.

To all whom it may concern:

Be it known that I, MATTIE R. WARD, a citizen of the United States, residing at Leesville, in the parish of Vernon and State of Louisiana, have invented a new, original, and ornamental Design for Curtain-Poles, of which the following is a specification, reference being had to the accompanying drawing, forming part thereof.

The figure is a front elevation of a curtain pole, showing my new design.

I claim:

The ornamental design for a curtain pole, as shown.

MATTIE R. WARD.

In presence of—

W. W. THOMPSON,
I. B. ALFORD.
